UNITED STATES PATENT OFFICE.

ROBERT M. HUDDLESTON, OF SAN FRANCISCO, CALIFORNIA.

METHOD OF REMOVING CAN ENDS.

1,257,285.

Specification of Letters Patent. Patented Feb. 19, 1918.

Application filed January 25, 1917. Serial No. 144,853.

To all whom it may concern:

Be it known that I, ROBERT M. HUDDLESTON, a citizen of the United States, residing at the city and county of San Francisco and State of California, have invented new and useful Improvements in Methods of Removing Can Ends, of which the following is a specification.

This invention relates to a method of removing lock seam ends from can bodies; and has for its object to accomplish the removal of the can end in a quick and convenient manner without in any way injuring the can body, and at the same time leaving the flange on the can body in condition to receive another end.

In the filling of cans it frequently happens that it is necessary to remove the top after it is once locked and sealed in position, on account of irregularity in the weight of the contents, leakage of the end, or other causes. It is, of course, desirable that this be done without injuring the can body or unsuiting it for the reception of another top; and in the present invention I have provided a novel method and mechanism which accomplishes the result in a simple and facile manner.

One method of proceeding and a suitable apparatus for attaining the desired result is exemplified in the following description and illustrated in the accompanying drawings, in which—

Figure 1 shows an end elevation of a device embodying my invention and by the use of which my desired method may be carried out.

Fig. 2 shows a side elevation of the same.

Fig. 3 shows a detail view of the operating lever for moving the straightening and cutting rollers into engagement with the seam of the can.

Fig. 4 shows a plan view of the straightening and cutting rollers.

Fig. 5 shows a sectional view of the same.

Figs. 6 and 7 show detail views of the projectable blocks which carry the straightening and cutting rollers.

Fig. 8 shows a side elevation of the cutting and straightening rollers and carrying an operating mechanism therefor.

Fig. 9 shows a side elevation of the operating cam for the rollers.

Fig. 10 shows a perspective view of one of the projectable blocks carrying a roller.

Fig. 11 shows a diagrammatic view of various steps employed in connection with removing a can end, as carried on in my invention.

Fig. 12 shows a vertical, sectional view of the chuck which receives the can.

Fig. 13 shows a sectional view, in plan, of the same, taken on the line 13—13 of Fig. 12.

Fig. 14 shows a diagrammatic view of the cutting and straightening rollers and cam mechanism for projecting the same into operative position in proper sequence.

My method of removing can ends may be carried out by various agencies. However, it is described in connection with the machine disclosed in my co-pending application entitled "Machine for removing can ends," filed December 27, 1917, Serial No. 209,074.

In Fig. 11 of the drawings I show the successive steps involved in the process of removing the can end. The can body is shown at 10 and the top or end at 11, the latter being held in place by a lock seam which comprises a U-shaped channel 12, on the edge of the can body, and an interlocking portion 13, on the periphery of the can end to fit around the member 12 and enter the channel thereof. This is a type of seam in general use.

The first step in the removal of the can end consists in pressing the seam outwardly, which is accomplished by having a supporting and gripping ring comprising sections 36 to engage the seam at the upper, outer corner thereof, as shown at A in Fig. 11.

This ring causes a rotative movement to be imparted to the can. A straightening roller 15, with a thin beveled flange 16 of sharp inclination, engages beneath the seam, as shown at B in said figure, and when moved upwardly against the rotating can tends to force the seam outwardly from the can body.

A second roller 17, having a beveled flange 18 of less inclination next engages the partially straightened seam and moves it farther outwardly toward a right angular position relative to the axis of the can body, as shown at C in Fig. 11. Thereafter a straight-faced roller 19 engages the outstanding seam and completes the straightening thereof, as shown at D in Fig. 11.

The end of the member 13 on the can end in this position has a channel-shaped rim 20 hooked over the edge 110

of the flange formed by the member 12 on the can body, a shoulder 21 being formed where the supporting ring sections 36 grip the seam.

5 The next step is shown at E and consists in shredding the free end of the channel 20 on the member 13 by means of knife blades 22 arranged on the roller 19, or, if desired, on a separate roller. By cutting the end of 10 this channel into small strips the removal of the can end is facilitated.

The final step is shown at F and consists in severing the channel 20 by means of a cutting roller 23, on a line with the edge of the 15 outstanding member 12, leaving the parts as shown at G where the can end is free to be removed. The U-shaped member 12 will then be in the form of a shouldered, outstanding flange, as shown at H, which is 20 such that a new can end may be easily applied and joined to the can body as before with a lock seam, the shoulder portion 21 being of advantage in applying the new top.

With this understanding of the various 25 steps to be performed, the mechanism for carrying them out will now be described. As here shown, the machine comprises a frame 24 carrying a pedestal 25, upon which the can is placed, said pedestal being mounted 30 for rotation upon a spindle 26, the latter slidable in a bearing 27 on the frame and raised and lowered by means of a foot pedal 28. Above the pedestal, in spaced alignment therewith, is a chuck 29, as best shown in 35 Fig. 12. This chuck is secured to an arbor 30 and the latter is driven by suitable mechanism 31. The head of the chuck is cylindrical in form and carries a sleeve 32 slidable thereon and provided at its bottom with 40 a downwardly projecting flange 33 to fit within the circular ridge formed by the seam on the can end, when the can is raised into engagement therewith by means of the foot pedal.

45 Carried upon the sliding sleeve 32, by means of levers 34 pivoted on brackets 35, are arcuate ring sections 36, spaced radially from the sleeve. The upper ends of the levers 34 are provided with set-screws 37 50 working against inclined faces 38 formed on the chuck. As the sleeve 32 is raised upwardly by the can, the set-screws 37, riding against the inclined faces 38, cause the ring sections 36 to be moved inwardly into engagement with the upper, outer corners of 55 the seam and in this manner the can is securely gripped and held in place and rotated by means of the chuck.

Fixed to the frame of the machine, adjacent to the chuck and in a position surrounding the can, is an arcuate holder 39 carrying retractile blocks 40, upon each of which is journaled, at the upper inner end, one of the rollers 15, 17, 19 and 23. An 65 arcuate cam 41, movable in the holder

by means of a hand lever mechanism 42, has a plurality of projecting faces arranged to engage rollers 43 journaled in recesses on the intermediate portions of the blocks 40, whereby to raise said 70 blocks successively to present the straightening or cutting roller thereon in position to operate upon the seam in proper order.

The arrangement of the projectable blocks and cam mechanism therefor is shown in 75 diagram in Fig. 14, where it will be seen that the cam is moved in the direction of the arrow to raise the blocks and that the first projection thereof is relatively close to the roller 43 on the block carrying the initial 80 straightening roller; the second projection being spaced somewhat farther from the block carrying the intermediate straightening roller and the third projection being spaced still farther from the block carrying 85 the straightening and shredding roller 19, etc., in order that said blocks will be projected in successive order, as indicated in Fig. 11. While it is immaterial whether or not the blocks remain in raised position, 90 after they have once performed their functions, nevertheless the shape of each cam, projection is such as to allow the block to recede after the work of the roller thereon has been accomplished. The operating lever 95 for the cam has a limited movement on account of the provision of stops 44 and a spring 45 is provided to return the lever and cam to normal position.

In the operation of the device according 100 to the present method the can to be opened is placed in upright position on the pedestal and the foot pedal depressed to raise the can into engagement with the chuck, whereupon the chuck acts to automatically 105 grip the rim of the can in the manner shown in Fig. 12. With the can gripped between the ring sections 36 and the sleeve 32 it will be rotated by the chuck to permit the straightening and cutting rollers to perform 110 their operations upon the seam thereof. The operating mechanism 42 is then moved to actuate the cam 41, causing the initial straightening roller 15 to be raised into position to engage the underside of the seam, 115 the ring sections 36 acting as an anvil to support the upper side of the seam. The rotation of the can is quite rapid and after a few revolutions of the same the seam will be partially pressed out. Further movement of the can will cause the intermediate straightening roller to be projected into engagement with the partially straightened seam and move it farther outwardly.

Next, the roller 19 will be brought into 125 operative position by the cam, completing the straightening of the seam and by means of the knife blades 22 shredding the free end of the channel-shaped periphery of the can top. Thereafter the roller 23 is brought 130

into position to sever the base of the channel 20 on a line with the edge of the outstanding flange of the can body, the gripping ring sections 36 coöperating with said cutting 5 roller to permit the complete severing of the channeled portion of the can end. The shredded and severed portion of the channeled rim 20 will readily fall away, leaving the can end free to be removed from the 10 can body. The operation is rapid and easy of control and the seam is straightened out and severed without in any way injuring the can body or spilling the contents thereof.

Various changes in the construction and 15 arrangement of the several parts herein shown and described may be employed without departing from the spirit of my invention as disclosed in the appended claims.

Having thus described my invention, what 20 I claim and desire to secure by Letters Patent is—

1. The method of removing a lock seam end from a can body, which consists in pressing out the seam at right angles to the 25 axis of the can, and cutting off the interlocking portion of the can end without mutilating the resulting flange on the can body.

2. The method of removing a lock seam end from a can body, which consists in 30 forcing the folded parts of the seam away from the body of the can, leaving a right angular flange on the can body, overlying which is the rim of the can end having a channel-shaped periphery surrounding the 35 outer margin of the flange on the can body, and severing the channeled portion of the can end on a line with the edge of the flange of said body, whereby the end may be lifted off with the flange on the can body 40 remaining intact to receive another end.

3. The method of removing a lock seam end from a can body, which consists in 45 forcing the folded parts of the seam away from the body of the can, leaving a right angular flange on the can body, overlying 50 which is the rim of the can end having a channel-shaped periphery surrounding the outer margin of the flange on the can body, and shredding the end of the channeled portion below the flange.

4. The method of removing a lock seam end from a can body, which consists in gripping the upper end of the seam at the outer corners, forcing the interlocked parts of the seam away from the can body to form 55 a right angled flange on the can body, overlying which is the rim of the can end having a channel-shaped periphery encompassing the outer margin of the flange, and severing the channeled portion of the can end on 60 a line with the edge of the flange, whereby the end may be lifted off, the flange on the can body remaining intact for the reception of another end and having a shoulder at the point where it was gripped.

5. The method of removing lock seam can ends from can bodies, which consists in severing the seamed rim of the can end along a line coincident with the joint in the seam where the retaining flange on the can body 70 will not be injured and where the can end and the locked portion of its rim will be free for separate removal.

6. The method of removing a lock seam can end from a can body, which consists in 75 pressing the seam outwardly from the body of the can and severing the rim of the can end on a line where the locked portion of the seam and the can end are free for separate removal and the retaining flange on the 80 can body is left intact.

In testimony whereof I have hereunto set my hand in the presence of two subscribing witnesses.

ROBERT M. HUDDLESTON.
